FOG GENERATOR FOR INSECTICIDES OR THE LIKE

Douglas W. Anderson, Palatine, Ill., assignor to Burgess
Vibrocrafters, Inc., Grayslake, Ill., a corporation of
Delaware

Filed May 11, 1961, Ser. No. 65,132

Term of patent 14 years

(Cl. D31—3)

Fig. 2

Fig. 6.

Fig. 1.

Fig. 3.

Fig. 4.

Fig. 5.

FIG. 1 is a front perspective view of a fog generator for insecticides or the like embodying my new design;

FIG. 2 is a front view;

FIG. 3 is a right side view, the side opposite thereto being substantially similar in appearance;

FIG. 4 is a top view;

FIG. 5 is a rear view of my new design; and

FIG. 6 is a vertical sectional view thereof taken on the line 6—6 of FIG. 3 and partly in full.

The essential features of the design reside in the portions shown in solid lines on the drawing.

I claim:

The ornamental design for a fog generator for insecticides or the like, substantially as shown and described.
